LAMP AND HEATER

Filed Dec. 10, 1926

UNITED STATES PATENT OFFICE

JACOB STUART SCHAFER, OF NEW YORK, N. Y.

LAMP AND HEATER

Application filed December 10, 1926. Serial No. 154,003.

This invention relates to an improvement in electrical apparatus, and the same has for its object to provide an apparatus which may be used for illuminating purposes or for heating or cooking. The apparatus may also be used simultaneously both for illuminating and heating or cooking.

My invention consists of a novel construction of a combined electric heater and electric table lamp, wherein I utilize the hollow base of the lamp structure as an electric heater, so that when the lamp is inverted the heater can be operated to heat the room or if desired to heat an article as water, etc.

15 A further object of this invention is to construct a table lamp with a hollow base, the latter being utilized as a heating compartment and adapted to operate simultaneously with the lamp.

20 The object of this invention is to provide a combined electric lamp and heater with special provisions to prevent the accidental operation of heater when the lamp is in normal position or when the lamp alone is desired to be used.

25 A further object is to provide a combined lamp and heater and automatic provision for turning off the current from the heater when the lamp and heater is tilted or overturned from its operative position.

30 A further object of this invention is to provide a combined electric lamp and heater and automatic provision for turning on and off the current to the heater.

35 A further object of this invention is the provision of a lamp and shade, the latter adapted to tilt on the globe of the lamp and prevented from falling by a loop carried on the lamp.

40 A further object of this invention is the provision of an asbestos or heating pad having depressions or channels for circulating air.

45 A further object of this invention is the provision of an electric iron and means to automatically shut off the current when the iron is tilted.

50 A further object of this invention is the provision of an article containing an electric heating element and means to automatically

shut off the current when the article is tilted.

A further object is to provide a combined toaster and hot plate having a central support for cooking and thin radiating wires for toasting.

55

In the drawings, Fig. 1 is a front view, partly in section, made in accordance with my invention.

Fig. 2 is a view of the device in an inverted position also showing the wiring arrangement.

Fig. 3 shows the arrangement of the shade before and after tilting.

Fig. 4 shows a plan view of the mat.

Fig. 5 shows a modified form of the wiring 65 involving the principle of my invention.

Fig. 6 shows an electric iron using the principle of my invention.

Fig. 7 shows a cigar lighter using the same principle somewhat modified.

70 Referring to the drawings, the numeral 1, denotes a standard for a lamp having its lower portion formed into a hollow base 2. To the upper part of the standard there is soldered or welded a sleeve 3, to which there 75 are integrally fixed abutments or supports 4. To the other end of the abutments there is fixed by welding or otherwise a ring 5.

Within the upper end of the standard 1, I place an ordinary key socket 5' having a 80 key 6.

The base is either stamped or spun and has two ridges 7 and 8 which will be hereafter explained.

85 A bulb 9 is placed in the socket.

A shade 10 made either of metal, parchment, silk or glass composition has a band or ring 11 made fast to the shade by any desired means, two depressed wires 12 and 13 ending in gripping springs 14 and 15 are attached to 90 the ring 11. The gripping springs 14 and 15 grip the bulb and permits the shade to tilt on the bulb.

The ring 5 acts as a limiting stop and additional support for the shade when it is tilted in one direction as seen in Fig. 3.

95 Fig. 2 shows the device in an inverted position, with shade removed. In this position the base 2 is utilized as a heater. The ridge 8 supporting a grid 16 and ridge 7 supporting 100

an asbestos board 17. A heating unit made of nichrome wire is disposed on the asbestos board and is held by terminals 19 and 20.

5 A tube 21 is arranged within the base 2 and connects to the base of socket 5. The other end of the tube 21 has a cap 22 with a threaded opening at its end. The tube 21 carries a mercury switch with two terminals projecting therefrom. Two openings 24, 25 are also provided in the tube 21 to enable the connections to be made.

10 The assembling of the heating unit is as follows: The tube 21, with the mercury switch 23 is screwed into the socket 5. On the tube 21 the cap 22 is set. Into the opening of cap 22 a screw 26 is set and carries the grid 16, held down by a washer 27. Under the depressed center of the grid I place several layers of mica 28 to prevent contact with 15 live resisting wire 29. A fibre bushing 30 is placed through the asbestos and surrounds the screw preventing contact with the live wire.

20 The mercury switch 23 is so arranged that the current flows through the switch only when the device is in its inverted or tilted position.

25 Any other switch operated by gravity as weight may be used.

30 The wiring arrangement is as follows: The wire 31 goes to terminal 19. The wire 33 is in contact with wire 31 and goes to one terminal of the socket 5. The wire 32 goes to the other terminal of the socket 5. One of the terminals of the mercury switch has a wire 34 leading into contact with wire 32. The other terminal of the mercury switch leads to the 35 terminal 20 of the resistance wire 29.

With this layout it is seen that either the 40 lamp alone can be used, or the heater alone can be used, or both used simultaneously.

The device is shown resting on a mat made of asbestos or any other fire resisting material. Depressions or channels 37 are for the 45 purpose of permitting a current of air to reach the central portion of the device and thus enable to cool it off faster.

50 Fig. 5 represents a modified wiring arrangement, 38 representing the lamp, 39 the heating coil, and 40 a push button switch. This enables the heater being in the upper position and no current running therethrough. The object of this is to cool the heating unit before turning back to normal 55 position.

Fig. 6 is a modified form of using the principle of my invention. The feature of this invention may be adapted wherever a heating unit is involved. In this instance I have 60 shown an electric iron 41, having an endwise resting means 42. A plug 43 is so constructed as to carry the wires with the additional mercury switch 44. The wiring is shown in dotted lines. The heating unit is indicated 65 by numeral 45. If desired the plug and rest-

ing means 42 can be made in one or two units, and as such, may be adapted in existing irons.

Fig. 7 is still another modified form of using my invention. In this instance I have shown a cigar lighter having a hollow handle 70 50 and a box like member 51 open at its end, the electrical connection may be made either at the bottom of handle or end of box member 51, 52 is a resisting element for lighting a cigar, 53 is the mercury element when the lighter is in operation, 54 indicates asbestos or porcelain backing for the resistance element. To turn off the current you simply lay the device flat on a table or pad and to use it you lift it up vertically. 75 80

When a metal shade is used on the lamp, the outside is painted to harmonize with the surroundings, while the inside is polished and acts as a reflector when the shade is tilted.

85 Thus by the above described construction are accomplished among others, the objects hereinbefore referred to.

90 As many changes could be made in the above construction and many apparently widely different embodiments of this invention could be made without departing from the scope thereof. It is intended that all matter contained in the above description or shown in the accompanying drawings shall be interpreted as illustrative and not in a 95 limiting sense.

100 It is also understood that the language used in the following claims is intended to cover all generic and specific features of the invention herein described.

Having described my invention what I claim as new and desire to secure by Letters Patent is:

1. The combination of a lamp and a heater, 105 having terminals for receiving same, arranged at opposite ends of a standard, means for supporting the standard in a normal position, means to automatically turn on and off the heater.

2. The combination of a lamp and a heater, 110 having terminals for receiving same, arranged at opposite ends of a standard, means for supporting the standard in a normal position, means to automatically shut off the heater, if tilted or overturned from its operative position.

115 3. The combination of a lamp and a heater, electrical terminals for receiving same arranged at opposite ends of a standard, means for supporting the standard in a normal position, means for supporting the standard in an inverted position and means to prevent operation of heater when standard is resting in a normal position.

120 4. The combination of an electric lamp and an electric heater mounted respectively at opposite ends of a standard, a switch operatively connected to the lamp and a switch operatively connected to the heater, a base at one end for supporting the lamp in an 125 130

upright position, and a frame at the opposite end for supporting the lamp in an inverted position and the heater in an operating position, said lamp switch operative at will and the heater switch inoperative when said lamp is resting in a normal position.

Signed at New York, in the county of New York and State of New York this 13th day of November, A. D. 1926.

JACOB STUART SCHARF.
